DAVID LARSON, OF YONKERS, NEW YORK, ASSIGNOR TO OTIS ELEVATOR COMPANY,
OF JERSEY CITY, NEW JERSEY, A CORPORATION OF NEW JERSEY.

ALTERNATING-CURRENT POTENTIAL SWITCH.

981,930.

Specification of Letters Patent.

Patented Jan. 17, 1911.

Application filed May 7, 1908. Serial No. 431,497.

To all whom it may concern:

Be it known that I, DAVID LARSON, a subject of the King of Sweden, residing at Yonkers, in the county of Westchester and 5 State of New York, have invented a new and useful Improvement in Alternating-Current Potential Switches, of which the following is a specification.

My invention relates to electromagnetic 10 switches, and particularly to switches controlled by alternating current magnets.

One of the objects of the invention is to provide a switch of this kind in which only a small electromagnet and one consuming 15 only a small amount of current is required to hold the switch closed, and which at the same time will be free from the chattering noise ordinarily accompanying the use of alternating current magnets.

20 Other objects of the invention will appear hereinafter, the novel combinations of elements being set forth in the appended claims.

25 Referring to the accompanying drawings, Figure 1 is a side elevation partly in section of an electromagnetic switch mechanism embodying my invention; Fig. 2 is a front elevation of the same; Fig. 3 is a sectional view of the electromagnet taken on 30 the line *a—a* of Fig. 1; and Fig. 4 is an elevation of one part of the magnet frame.

35 The particular form of switch herein shown is what is commonly known in the art as a potential switch, and is adapted to be placed between the mains leading to a source of current supply and the apparatus operated or controlled by the current. The switch is adapted to be closed by hand, and 40 is then held in such position by the electromagnet until the line potential falls below a predetermined value, when the switch is automatically opened. As a switch of this kind is normally held closed and is often retained in such position continuously for 45 long periods of time, considerable electrical energy is usually consumed, and it is one of the special objects of the present invention to so design and arrange the parts that the switch contacts may be held firmly in 50 engagement by a comparatively weak magnetic pull, requiring only a small magnet, and at the same time to provide an electromagnet that shall be efficient when used with 55 an alternating current.

As shown in Fig. 1, the switch is mounted

on a base 1 of insulating material. A bracket 2 is secured to the base by bolts 3 and is provided with lugs 4 which form bearings for the rod 5 on which the switch arm 6 is journaled. A lug 7 formed on the 60 switch arm is adapted to strike a shoulder 8 on the bracket 2 and limit the outward movement of the switch arm as shown in dotted lines. The switch is provided with two pairs of contacts, as indicated in Fig. 2. 65 The stationary switch contacts 9 are held between clamping jaws 10 and 11, the jaws 10 extending through the base and forming binding posts 12. The movable contacts 13 are each provided with a stem 14 extending through a lateral projection 15 of the switch arm and forming a binding post. As the particular construction of the contacts and means for mounting the same form 70 16 part of the present invention, a detailed 75 description thereof need not be given herein. Any other suitable form of contacts may be used, if desired. Conductors leading to the apparatus to be controlled by the switch may be connected to the binding posts 12, the 80 circuit being completed in the usual way through the flexible cables 16, 16' connected to the potential mains.

The switch magnet M comprises a frame member 17 of magnetic material secured to 85 the base 1 by bolts 18. Bolted to the member 17 is a series of laminated plates 19 having projecting portions 20 extending into the magnet spool or winding 21, and forming an inner pole piece of the magnet. The 90 spool 21 may be secured in position by a key 22 extending through the spool and bolted with the plates 19 to the member 17. The armature or movable portion 23 of the 95 magnet core is also laminated, and, as here shown, comprises a series of thin plates or laminations bolted to the upper end of the switch arm which is also made of magnetic material.

In order to absorb the vibrations due to 100 current alternations, and thus prevent chattering, the following means is provided. A rod 24 is screw-threaded into the member 17 of the magnet frame and may be adjusted 105 by means of the knurled head 26 and locked in position by a nut 25. A cylindrical projection or core 27 extending outwardly from the head 26 forms a support for a heavy coil spring 28, the inner end of which is tightly wedged or clamped in a recess 29 in

the core 27, thereby securely holding the spring against displacement. Formed on the inner face of the switch arm opposite the spring 28 is a lug 30 which is recessed 5 to receive the end of the coil spring when the switch is closed. The rod 24 and spring 28 being made of magnetic material, form a path for the magnetic lines of force around the magnet coil. In order, however, to pro-
 10 vide a substantially closed magnetic path of sufficient cross-sectional area to reduce the magnetic reluctance to a minimum, the switch arm is provided with integral pro-
 15 jections or arms 31, 31' which extend in-
 wardly on opposite sides of the magnet frame 17 and in close proximity thereto, as shown in Fig. 4. These arms 31, 31' by increasing the self-induction in the magnet coil, decrease the current consumption.
 20 Plates 32 and 33 of asbestos wood, or other fireproof insulating material, may be used if desired to deflect arcs that might be produced at the contacts. A handle 34 is pro-
 25 vided for closing the switch. When the switch is closed, the coil spring 28 forms a yielding abutment for the switch arm, as the spring is strong enough to permit only a slight compression under the pull of the mag-
 30 net, and the position of said spring deter-
 35 mines the width of the air gap between the magnet poles. The rod 24 is usually so ad-
 justed that only a small air gap is main-
 tained between the magnet poles. The outer end of the spring 28 entering the recess in
 40 the lug 30 holds the switch arm 6 against any displacement that might occur owing to looseness in the pivotal connection of the switch arm, and thus holds the magnet core 13 in central position. The spring 28 ab-
 45 sorbs all vibration of the switch arm caused by current alternations in the magnet coil, and the switch arm is made quite heavy so that its inertia will prevent excessive vibration. The switch contacts 9 and 13 are yield-
 50 ingly held in engagement by the coil spring 35 which effects such engagement irrespec-
 tive of the adjustment of the spring 28. It should also be noted that the rod 3 is held firmly in its bearings due to the leverage ar-
 55 range ment.

It will be noted that the switch contacts are located near the fulcrum of the switch arm or lever 6, while the magnet is located at the outer end of the switch arm. By this arrangement a small magnet, owing to the 55 leverage obtained, is able to firmly hold the switch contacts together. The amount of current consumed is also much less than in the usual arrangement.

I have herein shown a construction em- 60 bodying my invention in one form, but various changes in details of construction and arrangement of parts might be made by those skilled in the art without departing from the spirit and scope of the invention, 65 and I wish therefore not to be limited to the precise construction disclosed.

What I claim as new and desire to secure by Letters Patent of the United States is:—

1. In an electromagnetic switch, the combination with a base, of a magnet coil, a magnet frame secured to the base and having a pole piece extending into said coil, a switch arm made of magnetic material, a pole piece carried thereby and movable into 75 said coil, and means for completing the magnetic circuit outside of said coil and through the switch arm.

2. In an electromagnetic switch, the combination of a switch arm, an electromagnet, 80 an armature for said electromagnet carried by the switch arm, a base on which the electromagnet is mounted, said base being pro-
 85 vided with a threaded opening, a threaded rod adjustably mounted in said opening, a lock nut for said rod, a stiff coil spring mounted on said rod and a lug formed on the switch arm, and provided with a recess to receive the end of said spring, said spring being positioned to hold the armature out of 90 contact with the magnet when the armature is in its attracted position.

In testimony whereof, I have signed my name to this specification in the presence of two subscribing witnesses.

DAVID LARSON.
